SAFETY RAZOR

Edward R. Wharton, Medford, Mass.

Application August 8, 1935, Serial No. 35,318

8 Claims. (Cl. 30—74.1)

My invention relates to safety razors and it has for its object to provide an improved device of this kind and especially to improve the construction of safety razors of the type shown and described in my Patent No. 1,984,243, granted December 11, 1934.

To this end I have provided a safety razor having the peculiar features of construction and mode of operation set forth in the following description, the several novel features of the invention being separately pointed out and defined in the claims at the close thereof.

In the accompanying drawings:

Figure 1 is an enlarged elevation, partly broken away and in section, of a safety razor constructed in accordance with this invention.

Figure 2 is a top plan view of the safety razor shown in Fig. 1.

Figure 3 is an elevation of the upper portion of the razor shown in Fig. 1 as viewed from one side of the latter.

Figure 4 is a section on line 4—4 of Fig. 1.

Figure 5 is an elevation of the outer section of the rotatable spindle-actuating member hereinafter described.

Figure 6 is an elevation of the inner section of the rotatable spindle-actuating member hereinafter described.

Figure 7 is an elevation of the spindle hereinafter described.

Figure 8 is a top plan view of one of the blade-flexing levers hereinafter described.

Figure 9 is a top plan view of the guard of the razor shown in Fig. 1 with the blade-flexing levers omitted.

Figure 10 is a sectional view of the parts at the upper end of Fig. 4 but with a blade in position on the guard and held in transversely bent condition by the blade-flexing levers.

Figure 11 is a view of a blade for use as a part of my improved razor.

Figure 12 is an enlarged elevation, partly in section, of a safety razor embodying an alternative form of my invention.

Figure 13 is a top plan view of the razor shown in Fig. 12.

Figure 14 is an elevation of the upper portion of the razor shown in Fig. 12 as viewed from one side of the latter.

Figure 15 is a sectional detail showing the bottom side of the guard.

Figures 16 and 17 are details of the lever-actuating spindle of the razor shown in Fig. 12.

Figure 18 is a section on line 18—18 of Fig. 12.

Figure 19 is a top plan view of one of the blade-holding levers of the razor shown in Fig. 12.

In the embodiment of my invention illustrated in Figs. 1 to 11, inclusive, 10 is the guard which is provided upon its back with a rigid perpendicular tubular handle 11 within which is disposed an endwise movable spindle 12. The handle 11 may, as shown, consist mainly of a metal tube telescopically and forcibly fitted at its inner end upon a tubular boss 13 that is an integral part of 10 the guard 10 and within which the upper portion of the spindle is slidably mounted.

The upper portion of the guard 10 is a plate-like structure formed at each end thereof with a pair of recesses 14 and at its middle with a transverse slot 15, Fig. 9, for the reception therein of the apertured hubs of two levers 17, Figs. 3, 4, 8 and 10, said hubs being pivotally connected with the guard by pintles 18 extending through the apertures of the hubs and also through apertures 16, Fig. 9, formed longitudinally through the guard. Each lever 17 is made upon its under side with three hubs, one at its middle and one at each end thereof, and upon its top with a longitudinal row of hooks 19 which project beyond the guard and also face outwardly toward the adjacent face-engaging side of the guard.

The body portion 20 of each lever 17 is of bar-like form and extends from end to end of the guard, being disposed between its pintle 18 and the longitudinal median line of the guard as viewed in plan, Fig. 2. Thus the body portion 20 provides an arm or "heel" to co-operate with the inner face of the blade of the razor, Figs. 10 and 11, as in my above mentioned patent.

Near its middle each lever 17 is made with an arm 21 whose free end occupies a recess 22, Figs. 4 and 7, formed in one side of the spindle 12, the latter being formed with two oppositely disposed recesses 22, one upon one side of the spindle that is occupied by the arm 21 of one lever and the other upon the opposite side of the spindle which is occupied by the arm 21 of the other lever.

The upper and lower side walls of each recess 22 provide abutment shoulders which act through 45 its arm 21 to swing the lever, of which the said arm forms part, on its fulcrum pintle 18 when the spindle 12 is moved endwise. It will also be observed that the engagement of the arms 21 with the flat bottom walls of the recesses 22 holds 50 the spindle against rotation so that it can only move endwise.

The inner end portion of the spindle 16 is threaded and telescopically associated with a spindle-actuating member herein shown as com- 55

prising an inner nut section or element 23, Figs. 1, 4 and 6, having threaded engagement with the threaded portion of the spindle and an outer finger-piece section or element 24, Fig. 5.

5 The outer end portion of the inner section 23 is made of reduced diameter to provide a stem 25, Fig. 6, which extends loosely through a smooth bore formed axially through the outer section 24, the outer end portion of said stem being threaded to receive upon it a nut 26 by which said section 24 is clamped rigidly against a pair of radial shoulders 27 provided at opposite sides of the stem 25, as shown in Fig. 1.

As shown in Fig. 4, the retaining nut 26 is provided upon its outer side with holes 28 for reception of the prongs of a spanner wrench by means of which the nut is applied to and removed from the stem 25.

20 The inner end of the finger-piece section 24 is made with a pair of oppositely disposed lugs 29, Fig. 5, whose proximate faces are flat and parallel and fit flatwise against a pair of oppositely disposed flat surfaces 30, Figs. 1 and 6, provided on stem 25 thus positively interlocking the two sections of the spindle-actuating member so that they cannot rotate relatively but can be separated when nut 26 is removed.

30 Between the ends of lugs 29 and a conical shoulder 31 provided upon the exterior of the inner section 23 immediately adjacent to its junction with the stem 25, the interior of the tubular handle 11 is made with an annular rib 32 whose opposite sides are beveled, as shown in Figs. 1 and 4, and serve as abutments for engagement 35 with the shoulder 31 and with the inner beveled ends of the lugs 29 so as to prevent endwise movement of the spindle-actuating member while permitting the same to rotate freely.

40 It will thus be clear that normally rotation of finger-piece section 24 imparts rotary motion to the inner section 23 which, in turn, moves the spindle 12 endwise. Also, that endwise movement thus imparted to the spindle in either direction acts positively through the arms 21 to swing 45 the levers 17 simultaneously in opposite directions on their fulcrum pintles 18. This construction dispenses with the use of the spring 22 of my patent above mentioned and provides for positive actuation of the blade-engaging levers 50 in both directions.

55 The blade 191, Figs. 10 and 11, is a thin flexible piece of sheet steel that is slightly longer than guard 10 and somewhat narrower, the two opposite longitudinal side marginal portions thereof having sharpened parallel cutting edges adjacent to and parallel with each of which is a longitudinal row of holes 33. The holes 33 of each row are relatively spaced apart the same as the hooks 19 of either one of the levers 17 and each hole is 60 made of a size and shape to permit the passage therethrough of the head of one of said hooks.

65 When the spindle 12 is at the limit of its inward movement the heels 20 of the levers 17 are against the outer face of the guard and the hooks 19 are positioned so as to register with the holes 33 of the blade and the latter can be placed upon the guard with each hook extending through one of the holes of the blade.

70 After the blade is placed upon the guard as just described the spindle-actuating member of the handle is rotated in a right-hand direction and acts to shove spindle 12 outwardly and the latter acts on arms 21 to swing the rows of hooks on levers 17 outwardly, away from each other. During the first part of this movement of the levers

the nose of each hook is caused to overlie the outer marginal portion of the blade immediately adjacent to its hole 33 and then, during the latter part of this movement, the heels 20 of the levers are swung into engagement with the inner face of the middle zone of the blade so as to bend said middle zone away from the guard as shown in Fig. 10 while the opposite side marginal portions of the blade are held by hooks 19 with the result that said side marginal portions are swung 10 downwardly toward the guard 10.

15 The opposite side marginal portions of the guard are curved or rounded away from the cutting edges of the blade and each is formed throughout its length with teeth alternating with 15 slots. Just inside of each row of slots the guard is formed upon its top side with a longitudinal channel or trough 34 which serves to catch and hold the lather that is scraped from the face by 20 the blade.

25 Each channel or trough 34 is bordered upon its inner side by an up-standing straight-edge or shoulder 35 which serves as a stop to limit the approach of the proximate cutting edge of the blade toward the guard and which also co-operates with the hooks of the adjacent lever 17 to hold the edge portion of the blade straight longitudinally.

30 The embodiment of my invention illustrated in Figs. 12 to 19, inclusive, is provided with a guard 10a at and integral with one end of a tubular handle 11a within which is slidably mounted the lever-operating spindle 12a, Figs. 12, 16 and 17, whose outer end is co-operatively associated with the arms 21a of the blade-holding 35 and flexing levers 17a.

35 The inner threaded end portion of the spindle 12a is telescopically associated with the interiorly threaded inner end of a single tubular spindle-actuating member 36 that is rotatably mounted 40 within the tubular handle 11a and held against endwise displacement therein by two spherical locking elements 37 occupying radial apertures 38 formed through the cylindrical wall of member 36, one at each side of the axis thereof. Normally the locking members 37 are held apart by a conical wedge element 39 herein shown as the inner end portion of a screw 40 that occupies the interiorly threaded outer end of the tubular spindle-actuating nut member 36. This wedge 45 element maintains the locking elements 37 projected somewhat from the radial apertures 38 so that they occupy an annular groove formed upon the interior of handle 11a thereby rotatably locking member 36 within said handle. By backing out the screw 40 member 36 is unlocked and 50 may be removed.

55 The part of the member 36 which extends beyond the handle 11a is constructed as a finger-hold 41.

60 As shown in Fig. 15 the guard 10a is constructed, as in my patent above mentioned, with two parallel slots 42 that are occupied by the elongate hubs 43, Fig. 18, of the levers 17a, one of which latter is shown in plan in Fig. 20. Each 65 hub 43 extends from end to end of its slot.

65 What I claim is:

70 1. In a safety razor, the combination with a flexible blade having opposite side cutting edges and formed with two rows of apertures each of 70 which is disposed adjacent to one of said side cutting edges, of a holder for said blade comprising a rigid guard provided upon its back side with a handle including a manually adjustable element as a part thereof; blade-holding mechanism 75

permanently and adjustably mounted on said guard having parts thereof extending through said apertures, and means through which adjustment of said element in either direction acts to positively adjust said mechanism and blade.

5. 2. In a safety razor, the combination with a flexible blade having opposite side cutting edges and formed with two rows of apertures each of which is disposed adjacent to one of said side cutting edges, of a holder for said blade comprising a rigid guard provided upon its back side with a handle including a manually adjustable element as a part thereof; blade-holding mechanism permanently and adjustably mounted on said guard having parts thereof extending through said apertures, and means through which adjustment of said element in one direction acts to positively adjust said mechanism so as to flex the blade in one direction and adjustment thereof in the opposite direction acts to positively adjust said mechanism so as to flex the blade in the opposite direction.

3. A safety razor constructed in accordance with claim 1 wherein said element consists of a threaded non-rotatable endwise movable spindle supported within said handle; a manually operable nut member rotatably supported within said handle and telescopically engaging said spindle, and means for holding said nut member against axial movement in either direction relatively to said handle.

4. A safety razor constructed in accordance with claim 1 wherein said element consists of a threaded non-rotatable endwise movable spindle supported within said handle; a manually operable nut member rotatably supported within said handle and telescopically engaging said spindle and means removably securing said nut member within said handle and for holding it against axial movement in either direction relatively thereto.

5. A safety razor constructed in accordance with claim 1 wherein said element consists of a threaded non-rotatable endwise movable spindle supported within said handle and which also includes an operating member for said spindle comprising an inner nut section rotatably mounted within said handle and telescopically engaging

said spindle, the outer portion of said nut member being made with an annular shoulder abutting a complementary annular shoulder provided upon the interior of the handle to hold said nut member against endwise movement in one direction, and also comprising an outer finger-piece section fixedly connected with the outer end of said inner section and abutting a complementary shoulder on said handle to hold said inner section against endwise movement in the opposite direction.

6. A safety razor constructed in accordance with claim 1 wherein said element consists of a threaded non-rotatable endwise movable spindle supported within said handle and which also includes a spindle operating nut member rotatably mounted within said handle and telescopically engaging said spindle, said nut member being made with a radial hole disposed opposite an annular groove provided upon the interior of said handle; a locking element movably mounted within said hole, and an axially adjustable wedge member carried by said nut member and engaging said locking element to hold the same partly within said groove so that said element prevents axial movement of said nut member relatively to said handle.

7. A safety razor of the class described, having a blade-holder comprising a rigid guard provided upon its back side with a handle; an endwise movable lever-operating spindle supported within said handle; means for moving said spindle endwise, and a pair of blade engaging levers pivotally and permanently mounted on said guard each of which is made with an arm for engagement with said spindle, the arm of one lever occupying a recess formed in one side of said spindle and the arm of the other lever occupying a recess formed in the opposite side of said spindle and both arms being co-operatively disposed with relation to shoulders provided on said spindle so that endwise movement of the latter in either direction acts through said shoulders and said arms to swing said levers in opposite directions.

8. A safety razor of the class described constructed in accordance with claim 7 wherein said arms embrace said spindle so as to hold the latter against rotation.

EDWARD R. WHARTON.
